UNITED STATES PATENT OFFICE.

JAMES TIMMS AND JAMES O. TIMMS, OF COLUMBUS, OHIO.

CAR-COUPING.

No. 905,958.

Specification of Letters Patent.

Patented Dec. 8, 1908.

Application filed July 2, 1906. Serial No. 324,379.

To all whom it may concern:

Be it known that we, JAMES TIMMS and JAMES O. TIMMS, residents of Columbus, in the county of Franklin and State of Ohio, have invented certain new and useful Improvements in Car-Couplings; and we do hereby declare the following to be a full, clear, and exact description of the invention, such as will enable others skilled in the art to which it appertains to make and use the same.

Our invention relates to improvements in car couplings, the object of the invention being to provide an improved lever constructed to move the locking device to lock set position and then throw the knuckle open, and the invention consists in certain novel features of construction and combinations and arrangements of parts as will be more fully hereinafter described and pointed out in the claims.

In the accompanying drawings, Figure 1 is a view in vertical cross section through the coupler showing the pin in locked position. Fig. 2 is a similar view showing the pin lock set, the tail of the knuckle being omitted, and Fig. 3 is a perspective view of a modified form of lever.

1 represents a coupling head, 2 the tail of a swinging knuckle, and 3 the locking pin to lock the knuckle in closed position. The locking pin 3, when in locking position projects through an opening or housing 4 in the bottom of the coupling head and is provided with a shoulder 5 to seat on a ledge 6 in the coupling head to support the pin in lock set position when moved to this position by our improved lever 7 as will hereinafter appear.

The lever 7 is fulcrumed between its ends to a depending lug 8 on coupling head 1 and its weighted lower end projects below the rounded or beveled lower end of pin 3, and this weighted end of the lever is curved or inclined on its upper face where it contacts with pin 3, so that the lifting movement of the lever will not only elevate the pin but will also exert cam action on the pin to force its shoulder 5 over onto ledge 6 and compel the pin to assume its lock set position when elevated.

The upper portion of lever 7 above its fulcrum which lies beside the side wall of the coupling head, is made with an arm or tongue 9 projecting through an opening in the wall of the coupling head and into a recess 10 in the rear or back of the knuckle tail 2, and this arm or tongue may project laterally from the lever

7^a as shown at 9^a in Fig. 3, to dispose the arm nearer the pivotal point of the knuckle so as to require but a slight movement of the lever to force the knuckle open. The upper end of lever 7 is connected in any desired manner with an operating rod or bar 11 extending to the side of a car in convenient reach of an operator.

The operation of our improvements is as follows:—When the upper end of lever 7 is drawn back by the rod or bar 11, the lower heavier end of the lever will be moved upwardly to elevate the locking pin 3, and also by reason of the cam action of the lever against the lower end of the locking pin will move the pin laterally until the shoulder 5 thereon rests on the ledge 6, thus supporting the pin in its lock set position. When the locking pin is thus set, the knuckle may be opened by the subsequent separation of the cars. As the knuckle moves to its open position, its tail engaging a shoulder on the coupling pin moves the latter laterally off the ledge 6 and supports the pin in its elevated position. When the knuckle is again closed the coupling pin which has been supported thereon, drops in front of the tail of the knuckle and locks the latter in its closed position. If the coupling be disengaged and it is desired to manually open the knuckle so as to be in a condition to couple, the coupling pin should be elevated as above explained, by an outward pull on rod 11 and upward movement of the lower end of lever 7. After the pin has been seated on ledge 6, the bar 11 should be pushed in thus reversing the direction of movement of the lever 7, and forcing the upper arm on tongue 9 into contact with the rear face of the tail of the knuckle. This movement of the lever forces the knuckle to its open position. During its opening movement the knuckle removes the pin from the ledge as above explained and supports it in its elevated position until the knuckle has been turned to its closed position.

Many changes might be made in the general form and arrangement of the parts described without departing from our invention and hence we would have it understood that we do not restrict ourselves to the precise details set forth but consider ourselves at liberty to make such slight changes and alterations as fairly fall within the spirit and scope of our invention.

Having fully described our invention

what we claim as new and desire to secure by Letters-Patent, is:—

1. The combination with a Janney type coupling, of a pivoted lever having one end adapted to engage the lower end of the locking device, and having a fixed arm near its other end to engage the tail of the knuckle, the said lever adapted when moved in one direction to move the locking device to a position where it will be supported and will release the knuckle, and when moved in the opposite direction to engage the knuckle tail to open the knuckle.

2. The combination with a Janney type coupling, of a lever pivoted between its ends to the outside of the coupling and hav-

ing one integral end projecting beneath the locking device for moving the latter to a position where it will be supported and will release the knuckle, and an integral arm 20 on the lever projecting through an opening in the side wall of the coupling and into a recess in the knuckle tail in position to force the knuckle open.

In testimony whereof, we have signed this 25 specification in the presence of two subscribing witnesses.

JAMES TIMMS,
JAMES O. TIMMS.
